UNITED STATES PATENT OFFICE

ARRIGO EUGENE MARCONETTI, OF BROOKLYN, NEW YORK, ASSIGNOR TO DORNBUSCH AGENCY, INC., A CORPORATION OF NEW YORK

DESIGN FOR FANCY PAPER OR SIMILAR MATERIAL

Application filed March 17, 1930. Serial No. 34,922. Term of patent 3½ years.

To all whom it may concern:

Be it known that I, ARRIGO E. MARCONETTI, a citizen of the United States, and resident of Brooklyn, in the county of Kings and State of New York, have invented a new, original, and ornamental Design for Fancy Paper, or Similar Material, of which the following is a specification.

In the accompanying drawing:—

The figure is a surface view of a piece of fancy paper or similar material with my design, and the area within the intersecting dot and dash indicating lines constitutes one complete unit of the design, the other portions being repeat units arranged around the complete unit.

I claim:—

The ornamental design for fancy paper or similar material as shown and described.

Signed at New York in the county of New York and State of New York this 5th day of March A. D. 1930.

ARRIGO EUGENE MARCONETTI.
